DESIGN FOR A MECHANIC'S WORKBENCH AND CABINET

Stuart N. Price, Jackson, Mich., assignor to Kent-Moore Organization Inc., Detroit, Mich., a corporation of Michigan

Application January 28, 1948, Serial No. 144,102

Term of patent 7 years

(Cl. D33—19)

To all whom it may concern:

Be it known that I, Stuart N. Price, a citizen of the United States of America, residing at Jackson, in the county of Jackson and State of Michigan, have invented a new, original, and ornamental Design for a Mechanic's Workbench and Cabinet, of which the following is a specification, reference being had to the accompanying drawing, forming part thereof.

The figures of the drawing are as follows:

Fig. 1 is a perspective view of a mechanic's workbench and cabinet showing my new design;

Fig. 2 is a plan view thereof; and

Fig. 3 is an end elevational view.

I claim:

The ornamental design for a mechanic's workbench and cabinet, as shown.

STUART N. PRICE.
